UNITED STATES PATENT OFFICE.

HENRY GOWER HOSE, OF BROOKLYN, NEW YORK, AND WILLIAM H. RAMSDELL, OF BRIDGETON, NEW JERSEY.

ROOFING-SUPPORTING STRIP.

Application filed October 19, 1925. Serial No. 68,330.

Our invention relates to roofing for dwellings and other buildings, and particularly to means for supporting such roofing in a secure and safe manner, and so as to produce a pleasing effect to the eye.

In recent years there has come into very extensive use, as a substitute for the old wooden shingle roof, what are known as composition shingles, which are composed of a base of felt or other suitable material, which may be impregnated with asphalt, and the outer surface of which may be covered with crushed slate or the like. This roofing material is usually cut either into single shingles, or into portions known in the trade as strip shingles, which simulate several shingles in a series, and the lowermost corner or a portion of the lowermost edge, of such composition shingles may be formed into an underfolded flap, both for the purpose of forming a "butt-end," which adds to the pleasing appearance of the roof, and for the further purpose of providing an interlocking means so that the entire series of composition shingles, whether single or strip, may form a unitary roofing structure. As an example of such a structure we refer to Letters Patent No. 1,402,361, granted to one of the present inventors January 3, 1922.

Although composition shingles such as are above referred to may of course be used in new buildings, a larger field for the same has been in the re-roofing of old buildings, and the practice is to lay the new roof of composition shingles directly over the old roof, which is usually composed of the old-fashioned wooden shingles. This practice has given complete satisfaction up to a comparatively recent time, as the composition shingles are of sufficient thickness and rigidity to maintain themselves in a flat position, notwithstanding the irregular stepped surface of the old shingle roofing upon which the new roofing is laid, but it is now found that a composition roofing which has been laid for a number of years over old wooden shingle roofing or the like, and which has been exposed to the heat of summer and the frost of winter and to the rain of both summer and winter, tends to become softened or weakened to such an extent as to lose the comparative inflexibility which it had when first laid and to sag down more and more as the seasons pass so that it finally comes

to follow more or less closely the contour of the wooden shingle roof upon which it is laid, and as the depressions and elevations of the wooden shingle roof usually do not coincide with the butt ends of the composition shingles and the spaces between the same, an unsightly effect is produced.

One of the principal objects of our invention is to obviate the sagging or falling of new roofing laid over old shingles or other irregular surfaces as above referred to, by providing a supporting device adapted to be placed between the old and new roofings, which supporting device shall be of such construction as to form, when placed upon the old roofing, a substantially regular surface, which supporting strip shall be simple in construction, light in weight while sufficiently strong, and which may be easily and quickly placed in position during the operation of re-roofing.

The invention consists in the novel construction, arrangement and combination, set forth in the claims hereof, certain embodiments of the same being illustrated in the accompanying drawings and described in this specification.

In the accompanying drawings,

Fig. 1 is a perspective view of a roofing, showing the old shingle roof near the ridge, a portion lower down being provided with strips constructed according to our invention laid upon the old shingles, and a portion near the eaves completed by the placing of the new roofing, comprising in this case strips each of which represents four shingles;

Fig. 2 is a perspective view of a portion of one of our supporting strips constructed according to one embodiment of our invention;

Fig. 3 is a similar view, showing another embodiment;

Fig. 4 is a sectional view showing on an enlarged scale a fragment of the old and new roofing, with our supporting strip, in position;

Fig. 5 is a view similar to Fig. 2 showing another embodiment of our invention; and

Fig. 6 is a similar view showing still another embodiment.

Referring to Fig. 1 of the drawings, 11, 11, represents a portion of the roof frame, upon which is placed in the usual manner the ordinary furring strips 12, 12. Wooden shingles forming a part of the old roofing are shown at 13, and supporting strips, con-

22
structed according to one form of our invention, as will be hereinafter more particularly described, are designated 14. The new roofing material, consisting of what are commonly called "strip shingles," is shown at 15. This new roofing material, or strip shingles, represents one form of same often employed for re-roofing, but it will be understood that our invention is equally adapted 16 for use in connection with any form of re-roofing material, whether of the type shown in the drawing, or interlocking shingles, or even ordinary simple felt roofing not of shingle form.

15 The supporting device is shown more particularly and on an enlarged scale in Figs. 2, 3, 5 and 6, which show different embodiments of the inventive idea, said figures, however, showing only a fragmentary part of the supporting strip, which in practice may be of a length of several feet, the width being substantially equal to the distance between the successive butt ends of the ordinary wooden shingle roofing. These strips we prefer to 20 make of plastic material, which may be molded or pressed into the desired form, although of course the strip may be made, though not so economically, of wood or other material. The plastic material referred to 25 may be for instance wood fibre thoroughly macerated, and mixed in some suitable proportion with a binder, as asphalt cement; or wood or paper pulp may be used in connection with some suitable binder; it may also 30 employ compressed saw-mill waste, in connection with a suitable binder. A quantity of the mixture may be then formed into the proper shape, as hereinafter described, by 35 hydraulic pressure in a mold. The strip 40 may be in the form shown in Fig. 6, but in order to conserve material as well as to 45 decrease the weight of the finished product, we prefer to hollow out the under side of the strip, either with one wide longitudinal 50 hollow, as shown in Fig. 5, or with two as shown in Fig. 2, or three as shown in Fig. 3, and it is obvious that any desired number 55 of hollows may be provided. On the upper surface of the strip we provide a groove 60 16 of sufficient width to receive the heads of the nails 17 employed in securing the strips, as shown in Fig. 4, which shows the nails with their heads lying in the grooves 65 16 with their upper surfaces flush with the surface of the supporting strips. These 70 grooves 16 also perform the function of indicating the lines in which the nails should be applied. The position of the nails is of course of less importance in the forms shown in Figs. 5 and 6, but in the forms shown in Figs. 2 and 3 the groove 16 lies directly over the rib 18, thus ensuring that the nails 75 should be driven through the thickest portion of the strip, where it is supported upon the old shingle, thereby preventing any

crushing of the strip in the operation of driving the nails. As a further guide to the nailing, the grooves 16 may be provided in the middle with a narrow and shallow guide-groove 19, into which the point of the nail 70 is inserted when the same is being driven in.

The operation and method of use of our invention will be obvious from what has been above said with regard to its construction and assembling into a finished roofing.

75

We are aware that devices have been to some small extent used in the art for preventing the irregular contour of a roof produced by the sagging of a composition shingle re-roofing, but such devices have 80 been costly, heavy, and in other respects impracticable. Such devices have been produced by forming from a suitable board or plank of wood, two wedge-shaped pieces by means of cutting the board longitudinally 85 along a plane extending from one corner of the cross-section of the board diagonally through the board to the opposite corner. It is obvious that the cutting along such a plane would be a slow, difficult and expensive operation, and that even with the greatest care such a cut would often deviate from the desired true plane, thus rendering one of the wedge-shaped pieces sought to be produced too small for use as a supporting strip, and leaving the other too large so 90 that it would require further planing to adapt it for such use. Another method of forming a wedge-shaped strip from a wooden plank or board would be to shave off the superfluous part, leaving only one wedge-shaped portion. Either of the above operations would obviously be very wasteful of material, and furthermore the resulting product would be much heavier than 95 necessary.

95

In the use of a supporting strip constructed according to our invention, however, the above objections are completely 100 obviated, our supporting strip being easily molded from suitable plastic material, without waste and without the necessity of any slow, difficult or expensive operation requiring skilled labor; furthermore, owing to the peculiar construction of our supporting strip, it is much lighter than the strips at 105 present known to the art, thus effectuating not only a great saving in material but also in freight and cartage charges for shipping the same. Also, when the strips are delivered to the building which is being re-roofed, they are much easier to handle and lighter to hoist to the roof and are much easier manipulated by the workmen. The weight upon the roof is also less. The groove in our strip also affords a placement 110 for the head of the securing nail so that the same lies flush with the surface of the strip, and the small groove furthermore instantaneously guides the point of the nail to 115

its proper position, thus expediting the work of re-roofing. Other advantages will occur to those skilled in the art to which this invention relates.

5 We do not limit ourselves to the particular embodiments of the invention which we have shown in the accompanying drawings and described in this specification, as it is obvious that various modifications may be 10 made in the same without departing from the spirit and scope of our inventive idea.

Having thus described our invention, what we claim as new and desire to secure by Letters Patents is as follows:

15 1. A roof structure for buildings adapted to lie over a pre-existing roof, comprising in combination the following elements and parts: a pre-formed filling-in member composed of moldable material and adapted to create a plane surface by filling in irregularities in said pre-existing roof, and a roofing laid over said plane surface.

20 2. A roof structure for buildings adapted to lie over a pre-existing shingle roof having a stepped structure; comprising in combination the following elements and parts: A pre-formed filling-in member composed 25 of moldable material and wedge-shaped in

transverse cross section, whereby it is adapted to lie in the depression produced by one of said steps, whereby a substantially smooth and unstepped surface is created, and a roofing laid over said smooth and unstepped surface.

3. In a roof structure for buildings, a 35 pre-formed filling-in member composed of moldable material and adapted to create a plane surface by filling in irregularities in a pre-existing roof, said filling-in member being provided with a groove or cut-out. 40

4. In a roof structure for buildings, a pre-formed filling-in member composed of moldable material and adapted to create a plane surface by filling in irregularities in a pre-existing roof, said filling-in member 45 being provided with a groove or cut-out in its upper surface adapted to facilitate the nailing of the said strip to said pre-existing roof and to serve as a guide for the insertion of the nails used for said purpose. 50

In witness whereof we have hereunto signed our names this 14th day of September, 1925.

HENRY GOWER HOSE.
WILLIAM E. RAMSDELL.
